MIXING VALVE

Frederic N. Beede, Pawtucket, R. I.

Application January 19, 1935, Serial No. 2,601

13 Claims. (Cl. 230—95)

My invention relates to a valve mechanism having several valved ports and means for selectively controlling the opening and closing of the ports individually and collectively to permit flow of fluids, such as, steam, air, atomized or vaporized liquids, and to effect admixture and projection thereof by an injector action; and this application is a continuation in part of my co-pending application, Serial No. 489,447, filed October 10 17, 1930.

In my said copending application, I have disclosed a process and mechanism for treating fabrics and garments, and have shown in the said application, the valve mechanism which forms 15 the subject matter of the present application, as applied to a garment pressing machine.

The mechanism forming the subject matter of the present application is adapted for use in mixing steam and air for the purposes mentioned in my said copending application, as well as for mixing 20 and projecting onto fabrics or garments air or steam and moth repellent or moth-proofing compositions of various types, whereby the composition will saturate the fabrics or garments. The foregoing are only illustrative uses of the 25 present invention, and the same may be used for many various purposes where the flow of fluids is to be selectively and collectively controlled.

In the accompanying drawings, I have illustrated one form of my valve mechanism applied to a portion of a garment pressing machine, and it is to be understood that both forms may be so applied or used for other purposes where fluids are to be admixed and sprayed.

35 In the drawings;

Fig. 1 is a right side elevation of parts of a typical type of pressing machine with some parts in section and with one form of valve mechanism such as shown in my said application applied 40 thereto, and shown partly in section and partly in elevation;

Figs. 2—6, are views in elevation of the valve of Fig. 1 and its operating mechanism showing different operative positions of the valve and its 45 controlling mechanism;

Fig. 7 is a view similar to Fig. 3 showing another form of valve;

Figs. 8 and 9 are central vertical sectional views 50 of the valve of Fig. 7 showing different positions of fluid flow control parts;

Fig. 10 is a view taken on the line 10—10 of Fig. 8; and

Fig. 11 is a view taken on the line 11—11 of Fig. 8.

Referring to Fig. 1 of the drawings, the numeral 2 indicates generally a buck or lower member of a garment pressing couple, the other member of which includes a head or movable member 5 supported by lever 3, which is fulcrumed on a suitable frame and operated by known mechanism, (not shown) such as disclosed in Patent 1,715,115, dated May 28, 1929. The head 5 comprises connected or integral upper and lower walls 10 and 11 respectively, enclosing a heating chamber 12 to which steam is supplied as by a pipe connection 13. The lower wall is formed to provide a distributing space or chamber 14 for the perforated cover plate 15. The buck is formed with a heating chamber 16 to which steam is supplied at any convenient point (not shown) and its upper side is formed to provide a receiving chamber 17 with a perforated cover plate 18 with a discharge opening or passage 18a, at any convenient point, to which a pipe 19 is connected to carry off air, steam and moisture at any convenient discharge point.

At a convenient point, which may be near the center, the upper wall 10 of the head has a dome 20, formed to receive a tubular portion 21 of a valve body 22, which, with its connected and associated parts, constitutes in one form a principal part of the invention mechanism. The lower end of the tubular portion 21 is threaded and screwed into a tapped hole 23 in the lower wall 11, for supply of air or steam, or a mixture of air and steam, or other fluids as hereinafter pointed out, to the distributing chamber 14. A gland nut 24 and washer 25 or other suitable packing are provided to seal the valve body where it enters the boss 20.

In the present illustrative embodiment of the invention, I have shown a steam chamber 26 formed in the upper portion of the body, to which steam is supplied from the heating chamber 12 through one or more holes 27. A steam valve seat 28 is formed at the top of a tubular formation 29 in a wall 30, and a steam nozzle 31 is detachably located (for instance as by a screw connection as shown) in the lower end of the tubular steam passage, with its end properly located, anterior to a throat 32 in the tubular portion 32a of the valve body, which has a Venturi formation for an injector effect, as will appear. A reciprocating valve support or valve stem 33 has a face or valve disc 34 of any suitable material cooperating with the valve seat 28, and a guide may be provided such as the head 35 of a screw 36 which retains the valve disc. The screw head reciprocates within the tubular steam passage 29 below

the valve seat and is flattened or channeled on each side to provide for steam passage. The upper end of the valve support or stem 33 is in the form of a sleeve 38 slidably mounted on a stud 39 at the center of a screw cap 40 which closes the upper end of the valve body, and a helical spring 41 is placed about the sleeve and compressed between the screw cap and the valve support to urge the valve to closed position. The 5 valve support or stem 33 has at one side a slot 42 to receive a lug 43 projecting from a stem or shaft 44 which passes through the body, in which it is revolvably mounted, with suitable packing (not shown). One end of the stem valve 10 operating shaft or stem 44 projects from the valve body at one side thereof, and has thereon a short arm 45 (Fig. 1) the end of which confronts an arm or lug 46 forming a part of one of the controlling levers, referred to below.

20 The valve body 22 is formed with a passage 48 leading from a port 48' at one side of the body to the upper end of the Venturi passage 32a. The face 49 of the body about the port is finished off flat to provide a seat for the face 50 of a valve or damper 51, which is pivotally mounted on a pin 52 in a lug 53 on the body. The damper has an integral lug 54, and a helical spring 55 is placed between this lug and another lug or spring socket 56 formed on the upper end of a lever 58, (Figs. 3 25 to 7), which is pivotally mounted on pin 52 independently of damper 51 and its lug 54.

The valve structure as a whole may vary considerably, the principal features being independently controllable valved ports arranged to 30 supply selectively one fluid or a mixture of several fluids to a passage such as the Venturi passage. The operating means may also vary greatly, but in the construction and arrangement shown in Figs. 1-6, inclusive, such means consists in associated levers having devices to operate the respective valves, or elements connected to the valves, and arranged for independent or cooperative manipulation, as follows:

The main operating lever 60 is forked at one 35 end providing arms located at opposite sides of the valve body fulcrumed on the ends of a shaft or pin 47 which passes through a bearing hole formed in the body below the port 48'. The lug or arm 46, above mentioned, is formed integrally 40 on one of the fork arms of the lever 60, and the other fork arm has at its end, adjacent the valve body, at the side opposite to lug 46, a short upwardly projecting lug or arm 61, one face and the end of which cooperates with lever 58, and the 45 other face or end cooperates with a face 62 of the damper 51 projecting laterally and parallel to the active valve face 50. Thus the lever arm 61 is always located between the lever arm 58 and the face or flange 62. Another controlling lever 65, 50 is pivotally connected at 66 to lever 60, and may be of channel section or have a flange overlying lever 60, to engage one end of a spring 67 which is held in a socket 68 in lever 60, tending to move the outward ends of the levers divergently. Lever 65 has a finger-pad 71 and lever 60 has a pad 70, these being located close together for 55 convenient finger manipulation. Lever 65 has a rearwardly extending arm terminating in a rounded or cam-like end 72, to cooperate in some 60 cases with the face 73 of a flange projecting laterally from the damper 51.

Spring 41 of the valve 34 acts through the valve, upper face of slot 42, lug 43, stem 44, and arm or lug 46 on lever 60, to normally hold the valve 34 65 shut and maintain the outward end of the lever

and the finger-pad in an upward position, as in Figs. 1 and 3; and spring 67 normally maintains the outward end of lever 65 and its finger-pad 71 in an upward position in relation to lever 60 and its pad 70, and the rear end 72 of lever 65 in relatively depressed position. Spring 67 is of less strength than spring 41 so that when the finger-pad 71 is depressed without first depressing pad 70, the outer end of lever 65 will move down, and continue with lever 60, while the rear end 72 of lever 65 is moved to a position to cooperate with face 73 of the air damper, and thereafter further depression of pad 71 will cause the lever 60 to be also depressed, to open the steam valve, as will appear. Spring 55 is of suitable strength and length 10 to normally maintain the lugs or spring seats 54 and 56 in their most separated positions (Fig. 1), and thus to move lever 58 to a position relatively close to the face of the damper (in an angular direction) as also shown in Fig. 3, and also to 15 allow for substantial relative angular movement of the lever and the damper in their various operations, as will appear.

For the initial operation, pad 70 of the lever 20 60 is depressed, without depressing pad 71, so 25 that the levers retain their normal relative positions. Lug or arm 61 is thus moved clockwise in Fig. 3 and acts on lever 58 to move it to position of Fig. 2 and in this movement the lever acting through spring 55 moves the damper 51 to closed 30 position, thus closing the passage substantially before the valve 34 is opened; and upon further depression of pad 70 the arm or lug 46 of lever 60 acts through arm 45, stem 44, and lug 43, to 35 fully open the valve 34. Steam will then flow down tube 32a and moisten the fabric or garment beneath plate 15.

The levers and associated parts are then in the position of Fig. 4. Lever 58 has been moved to its extreme counterclockwise position by movement of lug 61 to its extreme position in the clockwise direction, this further movement of lever 58 after closing of the damper being permitted by compression of spring 55. It will be noted in Fig. 4 that in the stated extreme downward position of lever 60, when its pad is depressed without depression of the pad 71 of lever 65, the latter remains in relatively elevated position, held so by spring 67, and the rear end 72 of the lever does not contact with flange 73 of the damper, 50 permitting the damper to remain in closed position and preventing any access of fluid to passage 48 and the Venturi tube. The valve 34 having been opened in the manner described, fluid or steam under desired pressure is discharged 55 from nozzle 31, through the tubular passage of the valve body to the distributing chamber.

I may then supply to the distributing chamber a mixture of fluids, with a propulsive effect. This is done by opening the valve 34 or allowing it to 60 remain open while the damper 51 at the same time is opened or remains open if it has not previously been closed. The desired valve operations may be effected by different modes of manipulation of the levers. Thus, if the lever 60 remains 65 in fully depressed position, as in Fig. 4, to open the damper 51 and supply the mixture, it is only necessary to shift one finger to pad 71 of lever 65 which then moves to the position of Fig. 6, elevating the rear end 72 of the lever into contact 70 with the flange face 73 of the damper and opening the damper, as also shown in Fig. 5, spring 55 being in this case fully compressed.

If the passage 48 communicates with the atmosphere, when the parts are in the position of 75

Fig. 6, air will be drawn through port 48' by the injecting action of the steam jet and will be admixed in throat 32a as explained in my said application. Obviously, if the passage 48 communicates with a source of supply of moth-proofing or moth-repellant compound, then the compound will be drawn in and projected with the steam to saturate garments or fabrics beneath plate 15.

If just previous to the application of the mixture, the levers are in normal or idle position, as in Fig. 3, with the valve 34 closed and the damper 51 open, to supply the mixture it is only necessary to depress pad 71 of lever 65. As the pad moves down to the level of the other pad 70, as shown in Fig. 5, with the forward portion of lever 65 engaging on lever 60, the rear end 72 of lever 65 is raised to engage flange 73 of the damper which is thus held open, while further depression of pad 71 causes full depression of lever 60 and the opening of valve 34 while the damper 51 remains open, the parts then being in the position in Fig. 6.

After the mixture has been supplied for the desired time, the levers are permitted to return to normal position, shutting off the supply through valve 34.

I wish it to be understood that the invention is not limited to the character of fluid which flows through nozzle 31 to create the injector action, nor to the fluid drawn through passage 48 for admixture with the first fluid.

In Figs. 7-11, there is shown a modification in the invention wherein the means controlling flow of steam, and air, are separately operated, and also provision is made for the admixture of other fluids with the steam, such for example, as a moth-proofing composition. The tube 80 of the casing is screw threaded at its lower end the same as the tube 21 of Fig. 1, and is also provided with a Venturi passage 81. The steam passage 82 corresponding to the passage 27 of Fig. 1 extends upwardly and communicates into a chamber 83 in the casing proper. The outer end of the casing 83 is closed by a plug 84 provided with a central recess 85 which receives the end 86 of a steam control valve. The plug 84 is also provided with an annular groove 87 in which is seated a coil spring 88 which exerts a pressure against the valve head. A washer 89 is seated in the outer end of the valve head and is held in place by screw 90. The washer is of sufficient diameter to cover the end of the annular flange or ridge 91 around port 92 separating chamber 83 from chamber 93. A packless valve stem 94 engages at one end the head 95 of screw 90, said head being located in the port 92 and being slotted in cross-section to establish communication between the chambers 83 and 93, when washer 89 is moved away from port 92. The valve stem is mounted through a sleeve or gland 96 having screw threaded engagement at 97 with one wall of the valve casing and at 98 with another wall of the valve casing.

A bell crank lever 99 is pivotally mounted on a pin 100 extending through the lever and an extension 101 on the valve casing. The pin 100 may be removably held in place by cotter pins 102 or the equivalent. The upper end of the bell crank 99 is formed with a rounded surface 103 engaging the outer end of the valve stem 94. An actuating lever 104 is forked at its upper end and pivotally mounted on a pin 105 extending through the extension 101 on the valve casing. The forked arms of the lever 104

are provided with cams 106 against the lower side of which the forward arms 107 of the bell crank 99 bear. Obviously, depression of the lever 104 from the dotted line to the full line position of Fig. 7 rocks lever 99 and forces the valve stem 5 94 and screw head 95 inwardly removing the washer 89 from the port 91 establishing communication between the passage 82, chamber 83 and chamber 93, so that the steam may flow through the said passage, chambers and port, 10 and downwardly through the jet 109, and then through the Venturi tube 81 to the source of escapement.

In the case of garment pressing machines, the steam would flow from the Venturi tube into the pressing head, and from the head through the garments into the buck. To facilitate dispersion or distribution of the steam throughout the head, I provide a conical member 110 at the lower end of the Venturi tube and connected 20 thereto as by means of a pin 111 extending through the tube and the member 110. Obviously the steam, or admixed fluids as presently described, issuing through the Venturi tube, will be dispersed as they pass the curved surfaces of 25 the member 110 in the space between the member and the lower end of the Venturi tube.

The Venturi tube 81 communicates at its upper end adjacent the jet 109 with a passage 112 leading down from the chamber 113 through 30 which the valve stem 94 and its surrounding sleeve 96 are mounted. The top of the chamber 113 is formed by tubular extension 114 on top of the valve casing proper, and the exterior of the extension 114 is provided with ridges 115 at 35 regular intervals, as shown best in Fig. 10. A cap 116 has the lower ends of its side walls turned in as at 117 and these rest on lateral projections 118 at the base of the extension 114. At opposite sides the cap is provided with depending lugs 40 119 which extend through a space between pairs of the extensions 118 and receive cotter pins 120 to hold the cap on the extension 114. Obviously, other retaining means may be employed if desired.

On the interior of the side wall of the cap 116, between the inturned lower end 117 and the top of the cap, is a felt lining 121. As shown clearly in Fig. 10, there are spaces 122 between the ridges 115 and the walls 114 and lining 121. Within the cap 116 is a plate 123 connected by a rivet 124 to a stem 125 which is mounted through a bore 126 in the top of the cap. To the lower face of the plate 123 is attached a felt disc 127, as by means of rivets 128.

There are spaced projections 129 on top of the cap. A pin 130 is mounted through the stem 125 and through the space between the projections 129 and also through the opposite arms 131 of a lever 132, as shown clearly in Fig. 11. Cotter pins 133 are shown retaining the pin in place. The lower ends of the arms 131 are formed with cam surfaces 134 to bear against the top of the cap 116.

When raising the felt disc 127 from the top 65 of the extension 114, the handle of lever 132 is raised from the dotted line position of Fig. 7 to the full line position thereof, which causes the cam surfaces 134 to bear against the top of the cap 116, so that the pin 130 is moved upwardly 70 drawing the stem 125 upwardly against the action of the spring 135, which is located in the bore 126. When the lever 132 and stem 125 are thus moved upwardly, the disc 127 is raised from contact to the extension 114, so that with the 75

steam valve open as shown in Fig. 8 and steam being sprayed through the jet 109, air will be drawn through the passage 112 with an injector action, chamber 113 and openings 122 to be admixed with the steam at the throat of the Venturi tube and projected therethrough. However when the lever 132 is lowered, moving the cam surfaces 134 from binding engagement with the top of the cap, the stem 125 and plate 123 are also lowered, so that the spring 135 forces the felt disc 127 tightly against the top of the extension 114, so that no air can be drawn through the passages 122 into the chamber 113. The closed position of the air valve is shown in Fig. 15. I also mount a pin 136 through one of the extensions 129 for engagement by the lower ends of the handle 132, to force the cap down in case of friction in the felt disc, or in case the spring 135 should break.

16 20 I have shown a tube 137 mounted through one of the walls of the valve casing proper and communicating into the passage 112. The other end of this tube may be connected to a source of supply of moth-proofing compound or other liquid, not shown. When the tube 137 is so connected and when the parts are in the position of Fig. 8, the steam issuing through the jet 109 will draw the air through the passage 112 for admixture with the steam; but when the parts 25 are in the position of Fig. 9, the steam issuing through the jet 109 will create a suction in the passage 112 drawing the moth-proofing compound through tube 137 for admixture with the steam and to be sprayed on garments or fabrics.

30 35 The steam pressure or velocity drives the admixed steam and air or steam and moth-proofing compound into the fabrics or garments to saturate them, when the valve is used for this purpose.

The reason for the provision of the felt or 40 soft fibrous lining 121 and disc 127 is to silence the flow of air through the valve. While the provision of this silencer is not essential to the invention, it is highly desirable, because without such silencer there is a very noticeable hissing sound 45 as the air is drawn through the valve. I have found that by covering the metal surfaces, which the air would otherwise directly contact, with the soft fibrous or felt covering, the hissing sound is very materially deadened.

50 I claim:

1. A device for controlling the flow of a single fluid and for effecting the admixture of several fluids and controlling the flow thereof comprising, a body having an outlet passage, a port communicating into said passage in such manner as to produce an injector action therein, valve means controlling communication between said port and a source of supply of fluid under pressure, a second port, a second passage leading from second port to said first passage adjacent said first port, valve means controlling the communication of said second port with a second source of fluid, and a plurality of selective means operable at will, for controlling said first and second valve means one 55 of said control means being operable to effect flow of said first fluid alone under pressure through said first passage and to close said second valve means and another control means being operable to cause said flow of first fluid to draw said second fluid through said second passage into the first passage for admixture therein with said first fluid by injector action.
2. A mixing device of the character described comprising a casing having a Venturi passage, an air passage leading to the Venturi passage and

having a port, a valve controlling the air port, means on said valve and port to muffle the sound of air drawn therethrough, a steam nozzle arranged to inject steam in said Venturi passage from adjacent the lower end of the air passage, 5 and a valve controlling the steam nozzle, and a plurality of selectively operable means for controlling said valves one of said means being operable on said valves to effect supply of steam alone and another of said control means being operable 10 on said valves to admit steam admixed with air through said Venturi passage.

3. A mixing device of the character described comprising a casing having a Venturi passage, an air passage leading to the Venturi passage and having a port, a valve controlling the air port, a steam nozzle arranged to inject steam in said Venturi passage from adjacent the lower end of the air passage, 15 a valve controlling the steam nozzle, a plurality of means for selectively operating said valves to effect supply of steam alone or steam admixed with air through said Venturi passage, each of said means being constructed and arranged to control the operation of two of said valves, and a third port leading into said second passage anterior to the steam nozzle and communicating with a source of liquid.

4. A mixing device of the character described, comprising a casing having a Venturi passage, an air port communicating with the Venturi passage, 30 a cap mounted over said port and having a fibrous lining to silence the flow of air through openings in said cap communicating with said port, a valve within said cap having a fibrous surface adapted to seat against said port to close the same, means to move said valve relative to said port to control the flow of air through said port and passage, and means to induce the flow of air through said port and passage.

5. A mixing device of the character described, 40 comprising a casing having a Venturi passage, an air port communicating with the Venturi passage, a cap mounted over said port and having a fibrous lining to silence the flow of air through openings in said cap communicating with said port, a valve 45 within said cap having a fibrous surface adapted to seat against said port to close the same, means to move said valve relative to said port to control the flow of air through said port and passage, a jet confronting said Venturi passage, and 50 a valve to control the flow of fluid under pressure through said jet and passage to induce the flow of air through said port when said first valve is open with respect to said port.

6. A device for controlling the flow of a single 55 fluid and for effecting the admixture of several fluids and controlling the flow thereof, comprising a body having an outlet passage, a port communicating into said passage in such manner as to produce an injector action therein, means controlling communication between said port and a source of supply of fluid under pressure, a second port, a second passage leading from said second port to said first passage adjacent said first port, means operable to close said second port and 60 open said first port in sequence, and means operable to open or maintain said second port open and open said first port in sequence.

7. A device for controlling the flow of a single 70 fluid and for effecting the admixture of several fluids and controlling the flow thereof, comprising a body having an outlet passage, a port communicating into said passage in such manner as to produce an injector action therein, means controlling communication between said port and

5 a source of supply of fluid under pressure, a second port, a second passage leading from said second port to said first passage adjacent said first port, means operable to close said second port and open said first port in sequence, and means operable subsequent to the operation of said first means to open said second port.

10 8. A device for controlling the flow of a single fluid and for effecting the admixture of several fluids and controlling the flow thereof, comprising a body having an outlet passage, a port communicating into said passage in such manner as to produce an injector action therein, means controlling communication between said port and a source of supply of fluid under pressure, a second port, a second passage leading from said second port to said first passage adjacent said first port, and means operable to open or maintain said second port open and to open said first 20 port in sequence.

25 9. A device for controlling the flow of a single fluid and for effecting the admixture of several fluids and controlling the flow thereof, comprising a body having an outlet passage, a port communicating into said passage in such manner as to produce an injector action therein, means controlling communication between said port and a source of supply of fluid under pressure, a second port, a second passage leading from said second port to said first passage adjacent said first port, a valve for controlling the opening through said second port, valve operating means, means connected to said valve and engageable by said operating means to close said valve, a second 30 valve operating means, and means connected to said valve and operable by said second operating means to open or hold said valve open.

35 10. A device for controlling the flow of a single fluid and for effecting the admixture of several fluids and controlling the flow thereof, comprising a body having an outlet passage, a port communicating into said passage in such a manner as to produce an injector action therein, means controlling communication between said port and a source of supply of fluid under pressure, a second port, a second passage leading from said second port to said first passage adjacent said first port, a valve for controlling the opening through said second port, valve operating means, means connected to said valve and engageable by said operating means to close said valve, a second valve operating means, means connected to said valve and operable by said second operating means to open or hold said valve open, and means interposed between and connecting said two means connected to the valve permitting the operation of

one of said means relative to the other means.

15 11. A device for controlling the flow of a single fluid and for effecting the admixture of several fluids and controlling the flow thereof, comprising a body having an outlet passage, a port communicating into said passage in such a manner as to produce an injector action therein, means controlling communication between said port and a source of supply of fluid under pressure, a second port, a second passage leading from said second port to said first passage adjacent said first port, a valve for controlling the opening through said second port, valve operating means, means connected to said valve and engageable by said operating means to close said valve, a second valve operating means, means connected to said valve and operable by said second operating means to open or hold said valve open, and resilient means interposed between and connecting said two means connected to the valve permitting the operation of one of said means relative to the other means.

20 12. A device for controlling the flow of a single fluid and for effecting the admixture of several fluids and controlling the flow thereof, comprising a body having an outlet passage, a port communicating into said passage in such manner as to produce an injector action therein, means controlling communication between said port and a source of supply of fluid under pressure, a second port, a second passage leading from said second port to said first passage adjacent said first port, a valve for controlling the opening through said second port, control means for closing said valve, and control means for opening said valve, said last named control means being operable against the action of said first control means.

25 13. A device for controlling the flow of a single fluid and for effecting the admixture of several fluids and controlling the flow thereof, comprising a body having an outlet passage, a port communicating into said passage in such manner as to produce an injector action therein, means controlling communication between said port and a source of supply of fluid under pressure, a second port, a second passage leading from said second port to said first passage adjacent said first port, a valve for controlling the opening through said second port, control means including a resilient connection for closing said valve, and control 30 means for opening said valve, said last named control means being operable because of said resilient connection against the action of said first control means.

FREDERIC N. BEEDE. 55
